CAN OPENER

Bert H. Johnson, Moline, Ill., assignor to Quad-City Engineering Co., Rock Island, Ill., a corporation of Illinois

Application July 3, 1948, Serial No. 36,961

7 Claims. (Cl. 30—8)

1

The present invention relates generally to can openers and more particularly to can openers of the type adapted to pierce the tops of cans to provide an opening through which the contents can be poured, or which can be used for drinking the contents from the can. The principal object of the invention relates to the provision of a novel and improved can opener which is simpler and less expensive to manufacture, but which is more efficient in operation than those heretofore known.

Another object relates to the provision of a can opener which is simpler in operation and can be operated with one hand. Heretofore, devices of this general class require the can to be placed with one hand and pierced by a lever actuated either by the other hand or by the foot of the operator. According to the principles of the present invention the can is set in position and pierced by one continuous movement, using only one hand. In fact, two cans can be pierced simultaneously by one operator, using both hands and two can piercing devices, thus expediting the work of opening a large number of cans.

A further object relates to the provision of a can opener from which the pierced can can be removed without spilling any of the contents. This is accomplished by virtue of the fact that the can is removed without the necessity for tipping the can.

Still another object has to do with the provision of a can opener which has only one moving part and, due to its simplicity of construction is easier to keep in a clean and sanitary condition.

These and other objects and advantages of the invention will be apparent to those skilled in the art after a consideration of the following description of one embodiment, in which reference will be had to the drawings appended hereto, in which

Figure 1 is a side elevational view of a can opener embodying the principles of the present invention showing the device in loading position prior to piercing a can, the latter being indicated in dotted lines;

Figure 2 is a view similar to Figure 1 but showing the device in can-piercing position;

Figure 3 is a top plan view showing the device in piercing position; and

Figure 4 is a front elevational view of the device in the position shown in Figures 2 and 3.

Referring to the drawings, in which like reference numerals refer to like parts throughout, the can opener comprises a fixed support 5 and

2

a can carrier or cradle 6 swingably mounted thereon. The support 5 is in the form of an angular bracket having a vertical back wall portion 7, an overhanging generally horizontal top plate 8, and a pair of laterally spaced vertical flanges 9, 10 depending along opposite sides thereof. Preferably, the bracket 5 is formed as an integral piece and has perforations 11 in the back wall 7 and other perforations 12 in the top plate 8 to receive screws or other suitable means for fixably securing the bracket 5 to any vertical support 14' or beneath a horizontal overhanging support 14, such as a counter or table, indicated in dotted lines.

15 The can carrier or cradle 6 comprises a bail-like portion 20 curved in a U-shape to define a pair of arms 21, 22 positioned beneath the plate 8 with the arms extending forwardly between the depending flanges 9, 10. The ends of the arms 20 21, 22 are provided with outwardly offset supporting portions 23, 24 which lie against the inner sides of the flanges 9, 10, respectively, and are pivotally mounted on the latter by means of a pair of coaxial pivot pins 25, 26, respectively, 25 near the forward ends of the depending flanges 9, 10.

The cradle 6 further includes a can carrying portion 27, which is preferably formed integrally with the mid-portion or rear of the bail 20 and depends therefrom. The portion 27 is curved on the same radius as the bail 20, which is slightly greater than the radius of the cylindrical can 30, to receive the latter and conform to its outer surface. The carrying portion 27 has near its lower end a pair of forwardly turned, laterally spaced lips 31, 32 providing abutments to receive and support the lower edge or bead 33 of the can to be opened. Between the two forwardly projecting lips 31, 32 is a downwardly extending tongue or handle portion 34, the purpose of which will become apparent later.

40 In its normal position of repose, the cradle 27 hangs on its pivot pins 25, 26 in an inclined position, substantially as shown in Figure 1, but can be swung upwardly and rearwardly into the piercing position of Figure 2 in which the bail 20 is horizontal and the portion 27 is vertical.

45 A piercing tool 35 is rigidly mounted by suitable means, as by screws 36, on the bottom of the plate 50 8 in a position to be straddled by the arms 21, 22 of the bail portion 20 when the cradle is in piercing position. The tool 35 comprises a solid pyramidal block of stainless steel or other suitable durable metal, and has an apex 40 positioned 55 forwardly toward the center of curvature of the

bail 20, a pair of rearwardly diverging, generally vertical sides 41, 42 and a bottom surface 43 inclined upwardly and rearwardly from the apex 40 to a substantially vertical transverse rear wall 44. The bottom surface 43 lies in a plane which intersects the planes of the sides 41, 42 to form a pair of cutting edges 45, 46.

The operation of the can opener is as follows:

With the cradle in inclined position of repose, the operator, holding the can 30 in one hand near the bottom thereof, passes the can rearwardly between the arms 21, 22 and places the can on the rear carrying portion 27 with the lower edge 33 on the lips 31, 32. A continuous rearward pressure against the can forces the latter, guided by the cradle, upwardly and rearwardly against the tool 35. The apex 40 pierces the top of the can at a point inwardly of its edge and the two cutting edges 45, 46 cut the can top along a pair of rearwardly outwardly diverging lines to form a triangular tongue 47 which is bent rearwardly and downwardly into the can by the bottom and rear surfaces 43, 44 of the tool 35.

The can is then lifted from the forwardly projecting lips 31, 32 and lowered away from the tool in a substantially level position. This is facilitated by the shortness of the lips and by the downwardly extending tongue 34, which can be engaged by the third or fourth finger of the operator's hand to disengage the edge 33 of the can from the lips 31, 32. The cradle 6 automatically swings downwardly and forwardly by gravity as the can is moved away, thus returning to its normal position of repose, ready for another operation. If desired, the operator can open two cans simultaneously if two can openers are mounted side by side beneath the counter or on the side of a wall.

Once the piercing action has started, the camming action of the inclined bottom surface 43 of the tool against the tongue 47 cut in the top of the can 30 tends to urge the can rearwardly against the carrying portion 27 and prevents the can from slipping off the lips 31, 32. The cut tongue 47 is forced down into the can where it is out of the way to permit pouring or drinking the contents without interference. The triangular shape of the opening cut by the tool, with the apex of the opening toward the center of the can permits emptying the can easily without another vent opening in the can.

The simplicity of the parts and the construction of the tool as a solid block facilitates cleaning and provides a more sanitary device than those heretofore known. The tool can be easily removed for replacement or sharpening by removing the two screws 36. The offset ends 23, 24 of the bail 20 provide a minimum of friction between the bail and the flanges 9, 10 and a wider entrance for the can.

I do not intend my invention to be limited to the particular details shown and described herein, except as set forth in the claims which follow:

I claim:

1. A can opener comprising in combination, a support, a piercing tool depending from said support, a can-carrying cradle disposed beneath said piercing tool and having a pair of arms spaced laterally to receive a can therebetween, means coaxially pivotally mounting the outer ends of said arms on said support on opposite sides of said tool, respectively, providing for upward swinging movement of said cradle and a can carried thereby into a position wherein said tool pierces the top of said can.

2. A can opener comprising in combination, an overhanging support, a piercing tool depending from said support, a can-carrying cradle swingably disposed beneath said piercing tool and comprising an upper bail portion pivotally mounted on said support by means providing for swinging movement toward and away from said tool about an axis extending between the ends of said bail portion and means depending from the mid-portion of said bail portion for receiving a can and serving as a carrier therefor to guide the same upwardly about said axis into engagement with said piercing tool.

3. A can opener as claimed in claim 2, including the further provision that said depending can-receiving means includes an abutment for supporting the edge of the can and a portion extending below said abutment serving as a handle for disengaging the can from said abutment.

4. A can opener as claimed in claim 2, including the further provision that said piercing tool comprises a pyramidal metal block positioned to be straddled by said bail in can-piercing position.

5. A can opener as claimed in claim 4, including the further provision that said pyramidal block has an apex positioned to pierce the can inwardly from the edge of the latter, said block having a pair of outwardly diverging, generally vertical sides having cutting edges thereon, and a bottom surface inclined outwardly and upwardly from said apex and engageable with the cut portion of the can to bend the same into the can.

6. A can opener comprising in combination, an overhanging support, a piercing tool depending from said support, a can-carrying cradle swingably disposed beneath said piercing tool and comprising an upper bail portion having its ends normally extending generally forwardly toward the operator to receive a can therebetween and pivotally mounted on said support by means providing for upward and rearward swinging movement about a transverse axis extending between the ends of said bail portion, into a can-piercing position in which said bail straddles said tool, said cradle also having a can carrying portion depending from the rear portion of the bail and having a forwardly projecting lip for supporting the bottom edge of the can, said cradle being swingable upwardly to guide a can therein upwardly into piercing engagement with said tool.

7. The combination set forth in claim 6, including the further provision that said overhanging support comprises a bracket having a horizontal plate and a pair of laterally spaced flanges depending from said plate, and said bail having its ends pivotally mounted on said flanges, respectively, said piercing tool being fixed to the bottom of said plate between said flanges.
